(57) CLAIM

The ornamental design for a stand with monitor, as shown and described.

DESCRIPTION

FIG. 1 is a perspective view of a stand with a monitor, showing the new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines shown in the drawings of the stand with monitor illustrate the environment of the claimed design and form no part thereof.
